DESIGN FOR A TEXTILE FABRIC OR SIMILAR ARTICLE OF MANUFACTURE

Raymond Harvey, New York, N. Y.

Application September 12, 1934, Serial No. 53,264

Term of patent 14 years

To all whom it may concern:

Be it known that I, Raymond Harvey, a subject of the King of Great Britain, residing in the Borough of Manhattan, city, county, and State of New York, have invented a new, original, and ornamental Design for a Textile Fabric or Similar Article of Manufacture, of which the following is a specification, reference being had to the accompanying drawing, forming a part thereof, and showing a face view of a piece of textile fabric embodying my design.

The design is intended to be repeated on the textile fabric as shown.

I claim:

The ornamental design for a textile fabric or similar article of manufacture, substantially as shown and described.

RAYMOND HARVEY.
